UNITED STATES PATENT OFFICE

96,860

DESIGN FOR AN AUTOMOBILE

James K. Ryan, Hollywood, Calif.

Application June 6, 1935, Serial No. 57,173

Term of patent 7 years

To all whom it may concern:

Be it known that I, James K. Ryan, a citizen of the United States, residing at Hollywood, in the county of Los Angeles and State of California, have invented a new, original, and ornamental Design for an Automobile, of which the following is a specification, reference being had to the accompanying drawing, forming part thereof.

I claim:—

The ornamental design for an automobile as shown.

JAMES K. RYAN.
